United States Patent Office

Des. 180,825
Patented Aug. 20, 1957

180,825

NAVIGATOR COMPASS

John M. Fields, Rochester, N. Y., assignor to Taylor
Instrument Companies, Rochester, N. Y., a corporation
of New York

Application September 4, 1956, Serial No. 42,816

Term of patent 14 years

(Cl. D52—1)

FIG. 1

FIG. 2

FIG. 3

Fig. 1 is a plan view looking down;
Fig. 2 is an end elevational view; and
Fig. 3 is a side elevational view of a navigator compass, showing my new design.

I claim:
The ornamental design for a navigator compass, as shown.
